(57) **CLAIM**

The ornamental design for a propane tank cover with access port caps, as shown and described.

DESCRIPTION

FIG. 1 is a top, right, front perspective view of a first embodiment of a propane tank cover with access port caps, showing my new design;

FIG. 2 is a bottom, right, front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, right, front exploded perspective view thereof, wherein the access port caps are not shown;

FIG. 10 is a top, left, rear exploded perspective view thereof, wherein the access port caps are not shown;

FIG. 11 is a top, right, front perspective view thereof, wherein the access port caps are shown removed from their respective access ports for clarity of illustration;

FIG. 12 is a top, right, front perspective view of a second embodiment of a propane tank cover with access port caps, showing my new design;

FIG. 13 is a bottom, right, front perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is a top, right, front exploded perspective view thereof, wherein the access port caps are not shown;

FIG. 21 is a top, left, rear exploded perspective view thereof, wherein the access port caps are not shown; and,

FIG. 22 is a top, right, front perspective view thereof, wherein the access port caps are shown removed from their respective ports for clarity of illustration.

(Continued)

The broken lines in FIGS. 1-22 are for the purpose of illustrating portions of the tank refill stand and environmental structure that form no part of the claimed design.

1 Claim, 12 Drawing Sheets
